UNITED STATES PATENT OFFICE.

FREDERICK H. WOLKENHAUER, OF BENSENVILLE, ILLINOIS.

FURNACE.

1,410,049.

Specification of Letters Patent. Patented Mar. 21, 1922.

Application filed September 24, 1917. Serial No. 192,901.

To all whom it may concern:

Be it known that I, FREDERICK H. WOLKENHAUER, a citizen of the United States, and a resident of the city of Bensenville, county 5 of Du Page, and State of Illinois, have invented certain new and useful Improvements in Furnaces, of which the following is a specification.

My invention relates to improvements in 10 furnaces and has for its object the provision of an improved construction of this character adapted to induce thorough combustion of fuel and thus prevent smoke and also adapted for the economical consumption of 15 fuel.

The invention consists in the combinations and arrangements of parts hereinafter described and claimed.

The invention will be best understood by 20 reference to the accompanying drawings forming a part of this specification, and in which,

Fig. 1 is a longitudinal section through the forward portion of a boiler furnace, embodying the invention,

Fig. 2, a front view of the same shown partially in section,

Fig. 3, a longitudinal section through the lower forward portion of the furnace looking in the opposite direction from that of 30 Fig. 1;

Fig. 4, an enlarged detail view of the forward portion of the grate employed in the furnace, and

Fig. 5, a partial top plan view of one forward corner of said grate.

The preferred form of construction as illustrated in the drawings comprises a suitable boiler furnace provided with a suitable 40 fire chamber 6, a return-flue boiler 7 and a draft flue 8, as indicated. A grate frame 9 is arranged in the fire chamber 6 and is mounted on bell cranks 10 on posts 11 therein. The bell cranks 10 are connected by links 12 with 45 operating handles 13 situated at the front of the furnace, all except the grate surfaces substantially as disclosed in my prior Patent, No. 1,160,233, granted November 16, 1915. The grate frame 9 is equipped with two shiftable 50 frames, one of said shiftable frames consisting of side bars 14 and cross rods 15 and the other consisting of side bars 16 and cross rods 17, said frames being connected by slot and pin connections 17', whereby they may be shifted relatively to each other or to the grate frame.

An operating handle 18 is connected with

the frame 14—15 and a similar handle 19 is connected with the frame 16—17 for manipulating the same, said handles being extended through the forward portion of the furnace as shown. Frame 14—15 is equipped with a plurality of grate bars 20, overlapping similar grate bars 21 on frame 16—17, all of said grate bars being provided with suitable perforations or openings 23 for the 60 passage of the draft and the discharge of ashes. By this arrangement it will be observed that the grate bars 20 and 21 may be alternately shifted forwardly by manipulating the handles 18 and 19, and then simultaneously shifted rearwardly to effect rearward feeding of the fuel on the grate and also agitation of said fuel to discharge the ashes therefrom.

An apron 24 is hinged to the forward wall 75 of the fire chamber 6 and rests loosely on the forward rod 15, thus permitting of vertical adjustments of the grate, but compelling passage of the draft therethrough. A similar apron 25 is hinged to the forward grate 80 bar 20 and rests loosely upon the apron 24 for the same purpose.

A bridge wall top 26 is rigidly mounted on the rear end of the grate frame 9 and an apron 27 is mounted upon a rocker shaft 85 28 to seal the gap between the rearmost grate bar and said bridge wall top. The apron 27 is operated by means of a rocker arm 29 and an operating handle 30 as indicated to permit passage of draft when desired and also 90 to discharge accumulations of ashes. A hollow fire arch 31 extends across top of fire chamber 6, above the grate frame 9 and is equipped with a plurality of discharge openings or slits 32 arranged transversely in the 95 lower side thereof, as shown. The interior of arch 31 is connected by means of a pipe 33 provided with a valve 34 with the discharge of a blower casing 35 mounted as shown, and operable by means of a pulley 36. The 100 blower casing is provided with an intake communicating with the atmosphere controlled by a valve 37 operated by an arm 38 and also with an intake 39 equipped with a similar valve leading into the draft flue 105 8 whereby either air from the atmosphere, or smoke from the flue 8, or a mixture of the two may be discharged into fire arch 31 and thence into fire chamber 6, immediately onto the fuel therein, thus promoting combustion and thorough consumption of the 110 smoke.

2
A branch discharge pipe 40, provided with a valve 41, leads from pipe 33 into the smoke flue 8 above blower 35 whereby, when desired, a blast of air may be introduced into said smoke flue to increase the draft therein, and thus promote combustion.

An apron 42 formed in hinged collapsible sections is swingingly connected to depend from the forward portion of grate frame 9 substantially even with the forward portion of the fire arch 31 and is equipped with an operating handle 43 for manipulating or adjusting the same.

Another discharge pipe 44 equipped with a valve 45, leads from the blower casing 35 into and through a flue 46 which, in turn, leads from the upper forward portion of fire chamber 6 into the lower rearward portion thereof, below the fire grate and to the rear of the apron 42. The pipe 44 is equipped with a discharge nozzle 47 discharging through the lower opening of flue 46 and by means of which a draft may be induced through said flue to withdraw a portion of the smoke and gases evolved from the coal on the forward portion of the grate and introduce them into the fire chamber below the grate and behind the apron, so that the same will have to pass upwardly through the rearward portion of the grate.

By this arrangement the fuel on the forward portion of the grate will be first transformed into coke and the gases evolved therefrom thoroughly consumed in the furnace. Then this coke is gradually fed along the grate under the fire arch where it is completely consumed by the combined actions of the drafts thereon. Any gases or smoke passing off through the flue may be withdrawn therefrom and introduced into the fire chamber through the fire arch 31 for further combustion.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A furnace comprising a fire chamber provided with a vertically adjustable grate and means for inducing a draft therethrough; a hollow fire arch extending across the top of said fire chamber above said grate, said fire arch being provided with one or more discharge openings in its lower side; means for withdrawing smoke from said draft beyond said furnace and discharging said smoke through said arch; and means

for drawing air from the atmosphere and introducing it into said arch, substantially as described.

2. A furnace comprising a fire chamber provided with a grate and means for inducing a draft therethrough; and a flexible collapsible apron depending from the forward portion of said grate, substantially as described.

3. A furnace comprising a fire chamber provided with a grate and means for inducing a draft therethrough; a hollow fire arch extending across the top of said fire chamber above said grate, said fire arch being provided with one or more openings in its lower side; a blower casing having intakes leading to said draft and to the atmosphere; valves in said intakes, a valved discharge pipe from said blower casing leading into said fire arch; and a valved branch from said discharge pipe leading into said draft, substantially as described.

4. A furnace comprising a fire chamber provided with a grate and means for inducing a draft therethrough; a hollow fire arch extending across the top of said fire chamber above said grate, said fire arch being provided with one or more openings in its lower side; a blower casing having intakes leading to said draft and to the atmosphere; valves in said intakes; a valved discharge pipe from said blower casing leading into said fire arch; a valved branch from said discharge pipe leading into said draft; and a discharge pipe leading from said blower casing and discharging under said grate, substantially as described.

5. A furnace comprising a fire chamber provided with a vertically adjustable and tiltable grate and means for inducing a draft therethrough; a hollow fire arch extending across the top of said fire chamber above said grate, said fire arch being provided with one or more discharge openings in its lower side; a blower casing having intakes leading to said draft and the atmosphere; valves in said intakes; a valved discharge pipe from said blower casing leading into said fire arch; a valved branch from said discharge pipe leading into said draft; a depending apron on said grate; a flue leading from the upper portion of the fire chamber forward of said apron into the lower portion of said fire chamber under said grate and to the rear of said apron; and a discharge pipe leading from said blower casing through said flue and discharging therethrough under said grate, substantially as described.

6. A furnace comprising a fire chamber provided with a vertically adjustable and tiltable grate and means for inducing a draft therethrough; a hollow fire arch extending across the top of said fire chamber above said grate, said fire arch being pro-

vided with one or more discharge openings in its lower side; a blower casing having intakes leading to said draft and the atmosphere; valves in said intakes; a valved discharge pipe from said blower casing leading into said fire arch; a valved branch from said discharge pipe leading into said draft; a depending apron on said grate; a flue leading from the upper portion of the fire chamber forward of said apron into the lower portion of said fire chamber under said grate and to the rear of said apron; a discharge pipe leading from said blower casing through said flue and discharging therethrough under said grate; and means on said grate for feeding fuel thereon past said arch, substantially as described.

7. A furnace comprising a fire chamber provided with a grate and means for inducing a draft therethrough; a hollow fire arch

extending across the top of said fire chamber above said grate, said fire arch being provided with one or more discharge openings in its lower side; means for discharging products from the fire chamber through said fire arch; an apron depending from said grate; a flue leading from the upper portion of said fire chamber forward of said grate to the lower portion of said fire chamber rearward of said grate; and means for inducing a draft through said flue, substantially as described. 25 30

In testimony whereof I have signed my name to this specification in the presence of two subscribing witnesses.

FREDERICK H. WOLKENHAUER.
